(57) **CLAIM**

The ornamental design for a drinking cup lid, as shown and described.

DESCRIPTION

FIG. 1 is a front, right and top perspective view of a drinking cup lid, showing our design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the drinking cup lid in another state.

The broken lines depict portions of the drinking cup lid that form no part of the claimed design.

1 Claim, 9 Drawing Sheets
